UNITED STATES PATENT OFFICE.

LIZZIE ROYS, OF NEW YORK, N. Y., ASSIGNOR TO THE BUTTERICK PUBLISHING COMPANY, (LIMITED,) OF SAME PLACE.

DESIGN FOR A SKIRT.

SPECIFICATION forming part of Design No. 18,385, dated June 12, 1888.

Application filed May 18, 1888. Serial No. 274,315. Term of patent 3½ years.

To all whom it may concern:

Be it known that I, LIZZIE ROYS, of the city, county, and State of New York, have invented and produced a new and original Design for a Pattern of a Lady's Walking-Skirt; and I do hereby declare that the engraved prints accompanying this specification convey to any one accustomed to using paper patterns a clear understanding of how a garment made up by the pattern will appear.

The design shows a round walking-skirt that displays a long right-side drapery exhibiting deep upturning plaits in its back edge, a long narrow left-side drapery displaying draping plaits extending from the belt, a long full panel

between the side draperies that exhibits a deep smocking at the top, and a long full back drapery that displays loopings at the center and draping plaits in either side edge near the top.

What I claim as my invention, and desire to secure by Letters Patent, is—

The design for a lady's walking-skirt, as shown in the engraved prints accompanying this specification.
